UNITED STATES PATENT OFFICE.

GEORGE F. CARSON, OF MEMPHIS, TENNESSEE.

AUTOMATIC SAFETY GATE FOR RAILROAD CROSSINGS.

Application filed December 4, 1926. Serial No. 152,538.

This invention relates to safety gates where a highway crosses a railroad and has especial reference to such a device which will automatically close whenever a train approaching the crossing enters the particular block in which the crossing is located.

Among the objects of my invention are to provide means,

(a) For closing the highway against vehicles approaching the crossing;

(b) For absorbing the shock should an approaching vehicle strike the closed gates;

(c) For warning and relieving vehicles from damage during closing of the gates;

(d) For giving audible as well as visual warning during the closed and closing period of the gates; and

(e) For generally improving the details of construction and operation of the closure devices.

The means by which the foregoing objects are accomplished and the manner of their accomplishment, will readily be understood from the following specification on reference to the accompanying drawings, in which,—

Fig. 1 is a plan view of a highway crossing a double track railroad showing the gates in closed position.

Fig. 2 is a plan view on a larger scale showing one of the gates in closed position.

Fig. 3 is an elevation on the same scale of one of the gates showing the manner of its support from the post;

Fig. 4 is an end elevation on the same scale, of the supporting post and gate showing the buffer springs, and also showing, in section on the line IV—IV of Fig. 2, the subsurface structure supporting the gate;

Fig. 5 is a further enlarged section on the line V—V of Fig. 4 showing relation of the supporting post and the pivot post and having a corner of the cover plate of the subsurface box, broken away to show the position of the operating mechanism when the gate is open.

Fig. 6 is a similarly enlarged section on the line VI—VI of Fig. 4 with the cover plate of the box removed to show the gate operating mechanism with the gate in closed position.

Fig. 7 is a view on about the same scale as Figs. 2, 3 and 4, showing an actuating mechanism for the device.

Referring now to the drawings in which the various parts are indicated by numerals

10, 10 are gates, made up substantially of horizontal members 11 and vertical members 12, 13, the member 13 extending below the bottom of the gate and forming a pivot post 60 therefor. 14 are supporting posts and 15 stop posts for the gate. Adjacent the posts 14, are boxes 16, which are sunk in the ground, preferably with covers 17 substantially flush with the surface of the roadway.

From these boxes conduits 18 lead to a central box 19 which is preferably located between the two tracks of a double track railroad and which is adapted to contain actuating mechanism for the gates.

20 is a slot in the cover 17, through which slot the pivot post 13 projects with its lower end resting in a groove 21; both the groove and slot leading parallel with the roadway and toward the post 14. Disposed between

the member 12 and the post 15 are compression springs 22 and between the post 14 and the pivot member 13 are similar springs 23. The springs 22 are secured to a plate 24 which is clamped to the posts 15 and to a plate 25 against which the gate members 12 are swung when the gate closes.

Similarly the springs 23 are secured to a plate 26 which is clamped to the posts 14 and to a plate 27 against which the pivot post 13 rests.

The front end of the gate is swung from the top of the post 14 by a spring tension rod 28 and a tension rod 29 extends from the center of the gate similarly to the top of the post.

Secured to the lower portion of the pivot post 13, is an arm 30 which is connected by a rod 31 with a suitable operating mechanism comprising a horizontally rotatable plate 32. This plate is adapted to be oscillated by some form of actuating mechanism such as the reversible motor 33, acting through the shaft 34, worm wheel 35, worm gear 36 and vertical shaft 37. From the motor control circuits 38, 39, 40 and 41 lead preferably through conduits 42, to trips 43 located along the track at such distance from the highway as may be desired.

The rod 31 is provided at one end, with a slidably mounted section 44, which is limited in outward movement by a pin 45 which is slidable in a slot 46. 47 is a compression spring which normally holds the slidable end 44 in extended position.

Each of the gates is provided with a flexible arm 48 extending therefrom, on which arm is swung a sign plate 49 on

which may be imprinted any suitable or desired matter. The end 50 of the arm 48 is bent downward and then reversely bent to eliminate any projecting point. 51 is a red signal light for use as a night warning.

An electric bell 52 may be located on the posts or if desired located along the highway further from the tracks. In general the gates are to be located at sufficient distance from the crossing to provide standing space for machines which have been caught between them during the closing period and for such purpose they should be located at a distance ordinarily of about sixty feet from the tracks. Since the gates must close before the train reaches the crossing the "block" which governs the closing must be of considerable length, preferably about four hundred yards; that is the control switch must be that distance from the crossing. For double track, in order to avoid danger from a train approaching on the opposite track, the control switch opening the gates should be located at approximately the same distance beyond the crossing. The length of block suggested however, and distance of the gates from the crossing however are advisory only and would of course be regulated to suit the individual company making the installation.

In use the gates normally stand open in positions 10^A, 10^A shown dotted in Fig. 1. A train approaching the crossing strikes the top 43 and starts the motor 33. This shifts the plate 32 and causes the rods 31 to swing the gates to the positions shown across the highway, where they remain until the train passing out of the block strikes the second trip and starts the motor in reverse direction to swing the gates open.

While the gates are closed, should a vehicle strike them, the force of the blow would be minimized if not entirely absorbed by the springs 22, 23, and the spring 47 compressing would permit the arm 30 to move to the position 30^A, shown dotted in Fig. 6.

Having thus disclosed the invention, what I claim is:—

1. A safety device for highway-railroad crossings comprising a supporting and a stop post, disposed on opposite sides of said highway adjacent said railroad, a box adjacent said supporting post, said box having a slot in the top, and a groove in the bottom thereof leading toward said post, a rigid gate of width to span said highway when closed thereacross, having a pivot post at one end thereof stepped in said slot and groove and spaced from said supporting

post, a tension support extending from the free end of said gate to the top of said supporting post, buffer springs secured to said posts and adapted to lie between said gate and said posts when said gate is closed across said highway, and means for swinging said gate into closed position on the approach of a train and to open position on the passage of said train.

2. A safety device for highway-railroad crossings, comprising a supporting and a stop post, disposed on opposite sides of said highway, adjacent said railroad, a box adjacent said supporting post, said box having a slot in the top, and a groove in the bottom thereof leading toward said post, a rigid gate of width to span said highway when closed thereacross, having a pivot post at one end thereof stepped in said slot and groove and spaced from said supporting post, tension supports extending from said gate to the top of said supporting post, buffer springs secured to said posts and adapted to lie between said gate and said posts when said gate is closed, an arm secured to said pivot post, a central plate, means for turning said plate in one direction on the approach of a train and in the opposite direction on the passage of said train, and a compressible rod between said plate and said pivot post arm.

3. A safety device for highway-railroad crossings comprising a supporting and a stop post, disposed on opposite sides of said highway adjacent said railroad, a box adjacent said supporting post, said box having a slot in the top, and a groove in the bottom thereof leading toward said post, a rigid gate of width to span said highway when closed thereacross, having a pivot post at one end thereof stepped in said slot and groove, and spaced from said supporting post, a tension support extending from said gate to the top of said supporting post, a flexible, warning arm extending beyond the end of said gate, a sign board carried thereby, buffer springs secured to said posts and adapted to lie between said gate and said posts when said gate is across said highway, an arm secured to said pivot post, a central plate, means for turning said plate in one direction on approach of a train and in the reverse direction on passage of the train, and a rod connecting said plate and pivot post arm.

In testimony of the foregoing, I affix my signature.

GEORGE F. CARSON.
